UNITED STATES PATENT OFFICE.

HARRY A. HIGGINS, OF KENOSHA, WISCONSIN, ASSIGNOR TO THE COE BRASS MANUFACTURING COMPANY, A CORPORATION OF CONNECTICUT.

HYDRAULIC MACHINERY.

No. 894,737.

Specification of Letters Patent.

Patented July 28, 1908.

Application filed November 8, 1905. Serial No. 286,383.

To all whom it may concern:

Be it known that I, HARRY A. HIGGINS, a citizen of the United States, residing at Kenosha, Kenosha county, Wisconsin, have invented certain new and useful Improvements in Hydraulic Machinery, of which the following is a specification.

My invention relates generally to apparatus operated by hydraulic pressure and more specifically consists of an improved form of hydraulic machinery which is particularly adapted to the operation of hydraulic draw benches.

In hydraulic machinery heretofore constructed, in which separate sets of cylinders have been employed for producing the outward and return motion, a great length of bed has been necessary, and much floor space has been occupied thereby. My invention overcomes this difficulty by telescoping certain parts of the hydraulic mechanism. It also possesses other advantages of construction and operation hereinafter to be pointed out.

The best form of mechanism embodying my invention at present known to me is illustrated in the accompanying three sheets of drawings in which:

Figure 1 is a plan view of the apparatus. Fig. 2 is a side elevation and partial section on line 2—2 of Fig. 1. Fig. 2^a is a detail in section of the valves controlling the fluid supplied to the hydraulic cylinders. Fig. 3 is an enlarged horizontal section, with parts broken out, showing the hydraulic cylinders in section, the section being taken on the line 3—3 of Fig. 4. Fig. 4 is a vertical section on lines 4—4 of Fig. 3. Fig. 5 is a detail view in vertical section on line 5—5 of Fig. 1. Figs. 6, 7, 8 and 9 are respectively cross sections taken on lines 6—6, 7—7, 8—8 and 9—9, of Fig. 2.

Throughout the drawings, like reference figures indicate like parts.

51 (Fig. 2) indicates the floor or other support upon which the mechanism rests.

52 is the main bed supporting the right hand portion of the machine, said bed resting upon the standards 52^a, 52^b, 52^c, or other convenient supports. The left hand end of the machine is supported on separate standard 53.

54 and 54^a are two large hydraulic cylinders which I will call the main cylinders. Each of these is closed at the left hand end

and provided at the right hand, or outer end, with stuffing boxes 55, 55^a, through which work the piston plungers 56, 56^a. The stuffing boxes 55, 55^a, on the open ends of the main cylinders are connected by a yoke 59, 60 while the closed ends of the cylinders are connected by the yoke 10.

I have shown the hydraulic motor mechanism arranged to perform work in drawing tubes through a die. The outer ends of the plungers 56, 56^a, are connected together by a yoke 57, to which are attached the grippers or tongs 58 by which a tube 14 may be drawn through a die.

18, 18^a, are horizontal guides or slides on the bed trough 52, and 19 is a carriage sliding thereon. 20, 20^a, are long tubes passing through openings in said carriage (see Fig. 7) and having consequently a sliding connection therewith. The right hand ends of these tubes are screwed into the hollow yoke 20^b, which is mounted on the outer end of the bed 52.

The main piston plungers 56, 56^a, are made hollow, as shown in Fig. 3, and have preferably located in them cylinders 21, 21^a, of smaller diameter, which will just fit over the ends of the tubes 20, 20^a, which tubes extend through the hollow piston ends 22, 22^a, in which the inner cylinders 21, 21^a, are mounted. These piston ends 22, 22^a, are provided with stuffing boxes 23, 23^a, so as to form water tight joints with the tubes 20, 20^a.

24 represents a saddle sliding on guides 18, 18^a, to which is pivoted by means of the bolt 25, the jaws 58^a, 58^b, of the tongs or grippers 58. The rear ends of these jaws are connected by links 26, 26^a, to the pin 27 on the piston yoke 57.

The piston yoke 57 has the buffer 29, of rubber or other slightly yielding material, mounted on its rear side at the point of contact with the carriage 19. This carriage 19, has the spring dog 30, pivoted at 28 to its under side, said spring dog or catch being normally held up by the spring 31, into the position shown in Fig. 5, in which it is adapted to overlap and grasp the lower end of the pin 27, or other suitable projection on the piston yoke.

32 is a block with a curved surface set in the bed of the machine and adapted to coöperate with the tail 30^a of the spring catch 30, so as to trip the same when the carriage 19, moves over said block. 34 is a stop on the

under side of said carriage 19, arranged to strike the cross piece 35, which in this case is shown as the end of one of the troughs forming the bed 52.

5 36, Fig. 2, is a diagrammatic representation of a pump taking water from the tank 37, forcing it through the hydraulic accumulator 38 and pipes 39, 39^a and 41, to the main cylinders 54, 54^a.

10 39^b, is a branch pipe leading to the hollow yoke 20^b, and through it to the pipes 20 and 20^a. 39^c is a hand valve which may be used to regulate the flow through said branch pipe 39^b, but which is kept open during the operation of the machine.

15 40 represents the valve mechanism which controls the supply to the pipe 41 and discharge therefrom, said valve mechanism comprising the inlet valve 40^a, outlet valve 40^b, 20 and the lever 43, connecting the two.

20 42 is a pipe leading from the discharge valve 40^b back to the tank 37.

25 Feed pipe 41 has the branches 41^a and 41^b connecting with the two cylinders, as shown in Fig. 9.

30 In practice, the pipe 39^a leading from the pressure tank enters the valve casing about midway between the top and bottom thereof so that in the position of the valve 40^a in Fig. 30 2^a, the pipe is open and when the valve descends to its lowest position, the pipe is closed.

35 43^a, is a link connecting the valve lever 43 with the operating lever 44, which, as shown in Figs. 1, 2 and 8, is a hand lever, but has a lever arm 44^a of the bell crank 44^a, 44^c connected thereto for automatic operation, the two levers being pivoted at 44^b. This automatic operation is produced through the 40 sliding tappet rod 45, which slides in the guides 48^a, 48^b, on the bed, and carries tappet arms 46, 46^a with which the overhanging lug 49, carried by the piston yoke 57 co-operates. The tappet rod preferably has a spring 45 connection 45^a with the bell crank arm 44^a.

47, 47^a, (see Figs. 3 and 9) are anti-friction rollers journaled on the inner end of the piston plungers 56, 56^a, and adapted to roll on the interior of the main cylinders, 54, 64^a, and 50 support the piston plungers so as to prevent excessive friction and uneven wear.

55 The mode of operating my invention is as follows: A tube 14, being brought from the machine in which the same is prepared, the attendant pulls back the mandrel rod 11, as far as the loose motion connection 13^d will permit, thereby freeing the mandrel 12, from the die 15, and lifts said mandrel up far enough to permit him to slip the tube over 60 the same. The tube and mandrel are then dropped down again and the reduced end of the tube is shoved through the die 15, between the jaws of the grippers 58, the parts being in the position shown in Fig. 3. During 65 all this time, the pump 36 is running con-

tinuously, but the machine being in a position of rest, the valves 40^a and 40^b, are each half way open, and the water passes through said valves and back to the tank through the return pipe 42, without moving the hydraulic machinery. The tube being in the position as described, the attendant grasps the hand lever 44, and throws it to the left (looking at the machinery in the position shown in Figs. 1 and 2). This closes the discharge valve 40^b and opens the inlet valve 40^a. Water is accordingly forced through the inlet pipe 41 to the main cylinders 54, 54^a, and the plungers 56, 56^a, start toward the right hand on their outward stroke, carrying with them 70 the piston yoke 57. The outward motion of the piston plungers is of course opposed by the pressure of the water in the tubes 20, 20^a, and inner cylinders 21, 21^a, but as the effective area of said pressure is much less than the area of cross section of the main cylinders 54, 54^a, the pistons are driven out by the excessive pressure, as before described, and a portion of the water in the tubes 20, 20^a, and inner cylinders 21, 21^a, is forced out through 80 the reversing pipe 39^b and around into the main cylinders. 85

90 The first movement of the piston yoke 57, serves to straighten out the links 26, 26^a, and the jaw members 58^a, 58^b, thereby closing the 95 jaws of the tongs down upon the end of the tube 14, and gripping the same firmly, as shown in dotted lines in Fig. 5. After the links have been straightened out in this manner, further motion of the piston yoke moves 100 also the saddle 24, on which the tongs or grippers are pivoted, and the latter begin to pull the tube through the die.

105 When the piston yoke has traveled far enough for the buffer 29 to strike the carriage 19, the latter is carried along with it, and as soon as the tail 30^a of the spring catch 30 runs off the curved surface 32, the dog 30 comes up and overlaps the lower end of the pin 27, thereby locking the carriage and the 110 piston yoke together. When the carriage and piston yoke have reached the right hand limit of their travel, by which time the tube has been pulled through the die 15 and reduced throughout its entire length, the lug 115 49 strikes the tappet arm 46^a, and through the tappet rod 45 and spring connection to the bell crank arm 44^a, throws the valve system 40 into the reverse position, closing the inlet valve 40^a and opening the discharge 120 valve 40^b. The water in the main cylinders 54, 54^a, now having a free passage back to the tank 37, there is nothing to oppose the constant pressure still maintained through the reversing pipe 39^b, and tubes 20, 20^a, 125 against the interior cylinders 21, 21^a, and under the influence of said pressure, the carriage 19 and main pistons and piston yoke begin to move on the back stroke toward the left. The first effect of this motion is to 130

overtake the saddle 24 and open up the grippers through the link motion, thereby releasing the tube 14, which is removed by the attendant. When the carriage 19, has traveled so far on the return stroke that the stop 34, strikes the cross piece or partition 35, the spring catch 30, has been released from engagement with the pin 27 and the carriage stops, the pistons and piston yoke proceeding 10 until they reach a position shown in Fig. 3, when the tappet arm 46 is struck, by lug 49 and carried far enough to partially open both of the valves 40^a, and 40^b, thus leaving the machine in the position of rest until the operator inserts the new tube and again starts the 15 machine by completing the throw of the hand lever 44, as before described.

In order to prevent the dog 30 being lifted too high by the spring 31, in case the carriage 20 19 should rebound far enough to carry the tail 30^a off the curved surface 32, I provide a stop 33 for such upward motion of the spring dog.

As the weight of the plungers 56, 56^a, is 25 considerable, and they would rest heavily on the lower portion of the cylinder interior when driven home into said cylinders, I provide the anti-friction rollers 47, 47^a, which ride on the interior of said cylinders and prevent friction and wear.

The anchorage device for the mandrel rod may be adjusted by rotating the screw threaded rod 13°.

The speed of the return motion of the pistons 35 ton may be regulated by controlling the flow of fluid through the reversing pipe 39^b by means of the hand valve 39^c, and the surplus fluid delivered by the pump may be stored in the accumulator 38, to assist in accelerating the outward stroke of the pistons.

The advantages of my invention comprise the shortening up of the machine by telescoping the tubes 20 and 20^a containing the fluid for the reverse stroke into the main pistons; the supporting by means of the carriage 19 of the tubes 20, 20^a, midway of their length when they are withdrawn from the piston plungers; the automatic action of the apparatus throughout, except when in a 45 position at which a new tube must be introduced; the powerful and certain action of the gripping apparatus; the elimination of friction of the main plungers in the cylinders; and the ample provision for adjusting all 50 parts.

It is evident of course that various changes could be made in the details of construction illustrated without departing from the spirit and scope of my invention. Many features 55 of my invention can be employed in hydraulic machinery other than that of a draw bench. The supporting action of the carriage 19, could be applied to machine elements other than the particular tubes here 60 shown. The reversing mechanism could be

employed with hydraulic apparatus in which the telescoping features herein described might not be employed. These and other modifications, however, which would occur to the skilled mechanic, I should still consider within the boundaries of my invention. Other forms of loose motion mechanism might be substituted for the links 26, 26^a, which operate the gripper.

Having thus described my invention, I 75 claim:

1. The combination with the main frame and a hydraulic cylinder carried thereby, of a hollow plunger located in said cylinder and adapted to reciprocate therein, a second hollow plunger located in said first-named plunger and having its outer end open, means for causing a constant interior pressure on the second plunger, manual starting means for effecting an exterior pressure upon the first plunger 85 during the outward stroke and automatic means for effecting a release of said exterior pressure during the inward stroke and a release of said interior pressure at the end of the stroke.

2. The combination with the main frame and a hydraulic cylinder carried thereby, of a hollow plunger located in said cylinder, a second hollow plunger located in said first-named plunger and having its outer end 90 open, means for supplying a constant fluid pressure within said second plunger, initial manual means and automatic means for effecting an alternation of fluid pressure in said cylinder and a release of pressure within 95 said second plunger at the end of said alternation.

3. The combination with the main frame and a hydraulic cylinder carried thereby, of a hollow plunger located in said cylinder, a second hollow plunger located in said first-named plunger and having its outer end open, a pipe connecting with the outer end of the second named plunger and over which the said second named plunger is adapted to move 100 during its outer stroke, means for supplying said pipe with constant fluid pressure, initial manual means and automatic means for effecting an alternation of fluid pressure in said cylinder and a release of pressure in said pipe 105 at the end of the inward stroke.

4. The combination with the main frame and a hydraulic cylinder carried thereby, of a hollow plunger located in said cylinder, a second hollow plunger located in said first 110 named plunger and having its outer end open, a pipe supported by the main frame and having one end located in the opening in the end of said second named plunger, together with means for supplying fluid under constant 115 pressure to the said pipe and fluid under intermittent pressure to the hydraulic cylinder, said means comprising a pump, an open connection from said pump to said pipe, a connection from said pump to said hydraulic 120

4
cylinder, a valve for opening and closing said last named connection, a discharge connection for said hydraulic cylinder, a valve controlling the same, initial manual means for operating said valves and automatic means for effecting a single reciprocation of said plungers within the cylinder.

5. The combination of a reciprocating piston, cylinders of different diameter operatively arranged upon opposite sides of said piston, a source of constant hydraulic pressure, a constantly open connection from said source of hydraulic pressure to the smaller cylinder, a connection from said source of 10 hydraulic pressure to the larger cylinder, a discharge connection adapted to be connected with said larger cylinder and with said source of pressure, a pair of valves coöperating to control said connections and arranged when in mid-position to connect the 15 discharge with the larger cylinder and also with the source of pressure, manual starting means and automatic means for operating said valves to effect a single reciprocation of 20 said piston.

6. The combination of a reciprocating piston, cylinders of different diameter operatively arranged upon opposite sides of said piston, a source of constant hydraulic pressure, a constantly open connection from said 25 source of hydraulic pressure to the smaller cylinder, a connection from said source of hydraulic pressure to the larger cylinder, and a valve controlling said connection, a discharge connection to said larger cylinder having a valve controlling the same, manual starting means and automatic means for operating said valves simultaneously to effect a 30 single cycle of operations, whereby one complete reciprocation of said piston is effected.

7. The combination of a reciprocating element, a supporting frame provided with guides, a fixed element upon the supporting frame extending parallel with the guides and having a sliding connection with the reciprocating element, a carriage mounted on the guides and also having a sliding connection with the fixed element, and means for causing the carriage to move with the reciprocating 45 element during a portion of the latter's travel, but remains stationary at a point intermediate the limits of movement of the reciprocating element during the remainder of said travel.

50 8. The combination of a reciprocating element, a supporting frame provided with

guides, a fixed element upon the supporting frame extending parallel with the guides and having a sliding connection with the reciprocating element, a carriage mounted on the 60 guides and also having a sliding connection with the fixed element, and means for causing the carriage to move with the reciprocating element during a portion of the latter's travel but to remain stationary at a point intermediate the limits of motion of the reciprocating element during the remainder of 65 said travel, said means comprising a spring catch on the carriage adapted to engage the reciprocating element, and a stop for the carriage provided with mechanism for disengaging said catch.

9. The combination of a horizontally reciprocating piston, a supporting frame provided with horizontal guides, a carriage mounted on said guides, a pipe fastened at one end to the supporting frame, telescoping at its other end into the reciprocating piston and supported intermediately of its ends by the sliding carriage, a spring catch on the 75 carriage adapted to connect it with the reciprocating piston only when the latter moves into contact with it on the out stroke, a stop for the carriage at a point intermediate the extremities of the piston travel, and a 80 stationary curved member adapted to strike and disengage the catch when the return stroke of the piston brings the carriage against the stop.

10. The combination with a reciprocating 90 piston, cylinders of different diameters operatively arranged upon opposite sides of said piston, a source of constant hydraulic pressure, a constantly open connection from said source of hydraulic pressure to the 95 smaller cylinder, a connection from said source of hydraulic pressure to the larger cylinder, a discharge connection adapted to be connected with said larger cylinder and with said source of pressure, a pair of valves coöperating to control said connections and arranged when in mid-position to connect the 100 discharge with the larger cylinder and also with the source of pressure, manual starting means and automatic means for determining 105 the direction of effective pressure.

In testimony whereof, I affix my signature, in the presence of two witnesses.
